Dreo humidifier Aug. 29, 2024 found on May 15, 2025 at: <https://www.amazon.co.uk/Dreo-Humidifier-Ultrasonic-Humidifiers-White/dp/B0DF2Y9SH4/> (Year: 2024).*

Primary Examiner — Calvin E Vansant
Assistant Examiner — Jonathan E Fiencke

(57) **CLAIM**

The ornamental design for an air humidifier as shown and described.

DESCRIPTION

1. Air humidifier
2. Air humidifier
- 1.1 : Perspective
- 1.2 : Perspective
- 1.3 : Front
- 1.4 : Back
- 1.5 : Left
- 1.6 : Right
- 1.7 : Top
- 1.8 : Bottom
- 2.1 : Perspective
- 2.2 : Perspective
- 2.3 : Front
- 2.4 : Back
- 2.5 : Left
- 2.6 : Right
- 2.7 : Top
- 2.8 : Bottom

The broken lines shown in the figures depict portions of the air humidifier that form no part of the claimed design.

1 Claim, 16 Drawing Sheets
